(57) **CLAIM**

The ornamental design for a pen, as shown and described.

DESCRIPTION

FIG. 1 is a perspective view of a pen;
FIG. 2 is a front elevational view of the pen of FIG. 1;
FIG. 3 is a rear elevational view of the pen of FIG. 1;
FIG. 4 is a left side elevational view of the pen of FIG. 1;
FIG. 5 is a top plan view of the pen of FIG. 1; and,
FIG. 6 is a bottom plan view of the pen of FIG. 1.

The right side elevational view of the pen shown in FIG. 1 is opposite from and a mirror image of the left side elevational view of FIG. 4.
